Primary Examiner — Natasha Vujcic*Assistant Examiner* — Gilbert B Ford(74) *Attorney, Agent, or Firm* — Bridgeway IP Law Group, PLLC; Sang Ho Lee; Hyun Woo Shin**(57) CLAIM**

The ornamental design for a packaging container for cosmetics as shown and described.

DESCRIPTION

FIG. 1 is a perspective view of a packaging container for cosmetics, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIG. 7 show portions of the packaging container for cosmetics that form no part of the claimed design.

1 Claim, 6 Drawing Sheets(56)
